UNITED STATES PATENT OFFICE.

BENJAMIN F. McGUINNESS, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-TENSION MEANS FOR LOOMS.

SPECIFICATION forming part of Letters Patent No. 766,511, dated August 2, 1904.

Application filed December 21, 1903. Serial No. 185,948. (No model.)

To all whom it may concern:

Be it known that I, BENJAMIN F. McGUINNESS, a citizen of the United States, residing at Worcester, in the county of Worcester and 5 State of Massachusetts, have invented certain new and useful Improvements in Weft-Tension Means for Looms, of which the following is a specification.

My invention relates to weft-tension means for looms and to that class of looms for weaving heavy belting, matting, &c., in which very strong and thick filling, sometimes with a wire center, is used. In this class of fabrics it is desirable to have a good and uniform selvage, 10 and to make this the filling has to be drawn very tight after the shuttle has passed through the shed.

The object of my invention is to provide a supplemental attachment or mechanism located at each end of the lay between the shuttle-boxes and the reed and automatically operated after the shuttle has passed through the shed to grip and hold the filling and draw it tight on the forward movement of the lay 15 and release it on the backward movement of the lay.

My invention consists in certain novel features of construction of my improvements, as will be hereinafter fully described.

I have only shown in the drawings a detached portion of one end of a lay and my improvements applied thereto sufficient to illustrate the construction and operation thereof.

Referring to the drawings, Figure 1 shows a detached sectional view of a lay in its forward position with my improvements applied thereto. Fig. 2 corresponds to Fig. 1, but shows the lay in its rear position and my 30 filling-gripping mechanism in its opposite position; and Fig. 3 is a plan view of some of the parts shown in Fig. 1 and shows also the reed and a portion of the woven fabric.

In the accompanying drawings, 1 is the lay-sword, which is pivotally supported at its lower end, (not shown) and has a rocking motion in the ordinary way.

2 is the lay.

3 is the hand-rail, supported on uprights 4, secured to the back of the lay, as is customary. 50

I will now describe my improvements.

A stand 5 is secured to the back of the lay, and at the upper end of said stand 5 is pivotally mounted at 5' the rear end of the gripping jaw or lever 6. Said lever 6 has in this 55 instance a central longitudinal opening 6' therethrough, (see Fig. 3,) and the front end of said lever 6 is in this instance pivotally connected to one end of a link 7. The other end of said link is pivotally connected to an 60 arm or extension 8' on the filling-finger 8, which is pivotally mounted on a pin 9, supported on a plate 10, secured upon the top and the front surface of the lay and extends into a recess (shown by broken lines) in the 65 upper surface of the lay and is adapted to be raised and lowered through a central opening in the plate 10. The plate 10 has a projection 10' thereon which extends out from the front 70 of the lay.

The filling-finger 8 extends under the filling when the lay is in its rear position, as shown in Fig. 2, and when the shuttle is thrown through the shed. As the lay moves forward the finger 8 rocks on its pivotal support 75 and moves up to engage and move the filling 11 forward onto the projection 10' on the plate 10, as shown in Fig. 1, into position to be engaged and gripped by the flat gripping-surfaces 6" on the lever 6. (See Fig. 1.) 80

I will now describe the mechanism for actuating the gripping-lever 6 and the filling-finger 8 on the forward and backward movement of the lay. A vertically-moving rod 12 is loosely supported at its upper part in a swivel or rocking bearing in the lower end of the stand 5 and has its upper end 12' extending directly beneath and in engagement with a rearwardly-extending projection 6''' on the gripping-lever 6. The lower end of the rod 12 passes loosely through a swivel-bearing 13, supported on a stationary stand 14. On the extreme lower end of the rod 12 is a collar 15, secured in place by a set-screw 15'. A spiral 85 90

spring 16 encircles the rod 12 and bears at one end against the swivel-bearing 13 and at its other end against a collar 17, secured on the rod 12 by a set-screw 17'. The spring 16 acts 5 to hold the upper end 12' of the rod 12 in engagement with the lower surface of the projection 6" on the lever 6 and causes said lever to engage the filling 11 with a spring-actuated or yielding motion. On the forward 10 movement of the lay the spring 16 is compressed and the rod 12 is moved downwardly, as shown in Fig. 1, and on the backward movement of the lay the spring 16 expands and causes the rod 12 to move upwardly, as shown 15 in Fig. 2. On the forward movement of the lay the lower end of the rod 12 is held by the swivel-bearing 13; but the upper end of said rod moves with the lay and by reason of its swivel-support on the stand 5 moves on the 20 projection 6" on the lever 6 toward the pivotal support of said lever and causes said lever to rock and move down and bring the engaging surfaces 6" thereon onto the filling-thread 11 on the projection 10' on the 25 plate 10, as shown in Fig. 1, to grip the filling between the surfaces 6" and the projection 10'. The movement of the lever 6 through link 7 moves the arm 8' on the filling-finger 8 and causes said finger 8 to move 30 up out of the recess in the lay and engage and move forward the filling 11 onto the projection 10' on the plate 10, as shown in Fig. 1, in position to be gripped by the gripping-surfaces 6" on the lever 6. The continued 35 forward movement of the lay draws tight the filling 11, which is held by the lever 6, as shown in Fig. 3. On the backward movement of the lay the rod 12 at its upper end is carried back with the lay and also moved in 40 its swivel-support to cause its upper end to move out on the rearwardly-extending projection 6" on the lever 6 to the end thereof, as shown in Fig. 2. At the same time a spiral spring 18, attached at one end—in this instance 45 by a screw 19—to the stand 5 and at its other end by a screw 20 to the projection 6" on the lever 6, acts to move said lever 6 on its pivotal support and raise the outer end thereof and through link 7 and arm 8' move the finger 50 8 and lower said finger into the recess in the lay, as shown in Fig. 2, preparatory to another forward movement of the lay and the repetition of the operation of my gripping mechanism to grip and draw tight the 55 filling.

The advantages of my improvements will be readily appreciated by those skilled in the art. They may be applied to any loom of ordinary construction in which heavy filling-thread is 60 used, and they are entirely automatic in oper-

ation, requiring no additional work from the operator.

It will be understood that the details of construction of my improvements may be varied, if desired. 65

Having thus described my invention, what I claim as new, and desire to secure by Letters Patent, is—

1. In a loom, the combination with the lay, a stand secured thereto, a lever pivotally supported on said stand to have an up-and-down motion at its front end, a link or connector from said lever to a rocking finger adapted to engage the filling, and said finger, of means for operating said lever and finger 70 to lower the lever on the forward movement of the lay, and raise it on the backward movement of the lay, said means consisting of a vertically-moving rod, supported on and moving with the lay at its upper end, and loosely 75 held in a swivel-bearing at its lower end, and adapted to engage said lever at its upper end, a spring to actuate said rod, and a spring connected to said lever, substantially as shown 80 and described. 85

2. A weft-tension mechanism for looms, consisting of a lever pivotally supported at the rear of the lay, a filling-finger to engage and move forward the filling on the forward movement of the lay, into position to be engaged by said lever, connections between said lever and finger, and means for operating said lever to cause it to move down to engage the filling, on the forward movement of the lay, and to move up and disengage the filling on 90 the backward movement of the lay, substantially as shown and described. 95

3. A weft-tension mechanism for looms, consisting of a lever pivotally supported at the rear of the lay, a filling-finger to engage and move forward the filling on the forward movement of the lay, into position to be engaged by said lever, connections between said lever and finger, and means for operating said lever to cause it to move down to engage the filling, on the forward movement of the lay, and move up to disengage the filling on the backward movement of the lay, said means consisting of a vertically-moving rod supported at its upper end on and moving with the lay, and adapted to engage a projection on said lever and move forward with the lay, and loosely mounted in a swivel-support at its lower end, and a spring to actuate said rod, and a spring connected to said lever, substantially as shown and described. 105 110 115
